COMBINED DIAL AND HANDS FOR A CLOCK OR SIMILAR ARTICLE

James H. Sayih, Washington, D.C.

Application January 10, 1958, Serial No. 49,193

Term of patent 3½ years

(Cl. D42—1)

Fig. 1 is a front elevational view of a combined dial and hands for a clock or similar article, showing my new design; and

Fig. 2 is a side elevational view looking from the left of Fig. 1.

The dominant features of my design reside in the portions shown in full lines.

I claim:

The ornamental design for a combined dial and hands for a clock or similar article, as shown and described.
